ARTIST'S EASEL

Filed March 26, 1928

INVENTOR:

George W. Cahall,

by Murray G. Boyer
Atty.

UNITED STATES PATENT OFFICE

GEORGE W. CAHALL, OF PHILADELPHIA, PENNSYLVANIA

ARTIST'S EASEL

Application filed March 26, 1928. Serial No. 264,787.

My invention relates to easels and similar supporting structures designed for use by artists and others for the support of canvas stretchers and similar surfaces while being painted or ornamented, or for the display of pictures, paintings, and the like.

The main object of my invention is to provide a light, foldable, and easily operable structure, entirely self-contained and collapsible into a relatively small compass; such structure having a plurality of pivotally mounted foldable legs whereby it may be supported at various heights when said legs are in extended position, and said legs folding into parallel relation for transport purposes.

A further object of my invention is to provide adjustable means for supporting stretchers or pictures of various sizes in firm position and at various angles.

20 And a still further object of my invention is to provide a foldable palette support.

These and other features of my invention are more fully described hereinafter; reference being had to the accompanying drawings, in which:

25 Figure 1 is a perspective view of one form of easel constructed in accordance with my invention.

Fig. 2 is a side elevation of my improved easel in the folded condition, and

30 Figs. 3, 4, 5 and 6 are sectional views illustrating details of my invention.

Referring to the drawings, my improved easel comprises an upright or standard 1, which is slotted at 2, substantially throughout its entire length; the ends of such slot adjacent the top and bottom of the standard being closed. At the lower end of the slotted standard, a block 3 may be secured, and legs 4 are pivoted at 4^a to the lower end of said block 3. These legs may swing upon their pivotal connections from the position indicated in Fig. 1, to a completely folded condition; the dotted lines indicating a position intermediate the open and closed positions.

When open, the legs are maintained in the desired position by means of braces 5, pivotally connected to said legs at 5^a; the upper ends of said braces being pivotally connected 50 at 6, to a block 7, slidably mounted with re-

spect to the slotted standard 1. This connection is preferably in the form of a bolt 8, having a squared portion 8^a, fitting the walls of the slot; a thumb nut 9 for clamping said block 7 in the desired position being secured 55 to the outer end of said bolt 8, which extends from the back of the standard 1, and block 7, as shown in Fig. 6. Upon loosening the thumb nut 9, said bolt 8, together with the block 7, is free to be moved with respect to the slotted standard; the braces disposed between said block 7 and the legs 4 enabling the latter to be positioned as desired, upon moving said block 7 relatively to the slotted standard. When completely collapsed, as 60 shown in Fig. 2, the legs 4, and braces 5, are disposed in parallel relation with respect to the standard 1.

A rear supporting leg is indicated at 10, which is hinged at 10^a to the lower end of the 70 standard 1. Bracing members 11 are connected to this leg at the point 11^a; the upper ends of said bracing members 11 being operatively connected to a block 12 slidable with respect to the standard 1, being operatively 75 connected thereto by a bolt 13 passing through the slot 2 of the standard and having a thumb nut 13^a of the same type as those retaining the block 7 in place. I prefer the construction indicated, in which the braces 11 are secured to a member 14, which is hinged at 15, to the slidable block 12.

As indicated in Fig. 2, the rear leg 10, and the braces 11, will lie against the standard in parallel relation when the parts are in the 80 folded condition.

The standard carries a vertically adjustable support 16 for a picture, canvas stretcher, card, or the like, (indicated by the broken lines); such support having a bolt 17, 90 of the type referred to, which passes through the slot 2 of the standard 1, and is provided with a thumb nut 17^a, whereby such support may be held in the desired adjusted positions. In addition to the support 16, it is desirable 95 to provide retaining means for a canvas stretcher, card, or the like, and for this purpose I provide a rod 19, supported by a block 20, slidably mounted with respect to the upper portion of the standard; being held 100

thereto and retained in adjusted positions with respect to the standard by means of a bolt 21 of the type referred to passing through the slot 2, and having a retaining nut 21^a, see Fig. 3. To support the rod 19 and hold the same in adjusted positions, the block 20 carries an eye-bolt 23 through which said rod 19 passes; such eye-bolt having a retaining nut 24 and said rod having an outturned 10 ends 25 and 26, and each of said ends having a downwardly projecting portion indicated at 25^a and 26^a. In addition, the rod 19 is provided with a bend 27 adjacent one of said projecting ends. One of these projecting 15 ends, 25, for instance, is slightly longer than the other and is preferably disposed adjacent the upper end of the standard in position to engage the top of a canvas stretcher, as indicated by the broken lines in Fig. 1. The lower end, 26, is adapted to engage a card, or any type of small canvas resting upon the support 16. The bend 27 formed in the rod 19 is adapted to rest in the slot 2 of the standard 1, as indicated in Fig. 1; insuring 20 the perpendicular position of the retaining rod 19. By tightening up the nut 24 on the eye-bolt, the eye will be jammed in the supporting block 20, and hold said rod 19 in the desired position. The rod 19 is vertically adjustable with respect to the block 20, and the latter is adjustable with respect to the standard 1, so as to accommodate pictures, stretchers of various sizes and hold the same at various heights. 25

30 In Fig. 5, I have shown a modified arrangement, in which a rod 19^a is held to a modified form of block indicated at 20^a. In this arrangement two eye-bolts 23^a and 23^b are employed, and the block is angularly grooved at 20^b so that when said rod 19^a is raised to engage a picture after loosening the eye-bolts, it will tilt forward while its lower end will occupy the slot 2, as shown in Fig. 5. The block 20^a is recessed to accommodate the eyes of the bolts so as to jam the rod 19^a against the same.

35 I also provide a support for a palette, which may comprise a bar 30, adjustably held to the standard 1 by means of a bolt 31 passing through the slot 2 and through said support 30, which is disposed below the support 16; such bolt being of the type referred to and having a thumb nut 31^a whereby the palette support may be maintained in the desired positions. This support 30 carries arms 32, pivotally connected thereto and arranged to project forward to support a palette; such arms being foldable into substantially parallel relation with respect to the support when the easel is collapsed. While these arms are shown in the drawing as below the support 30, they may be arranged above the support by turning the latter, without departing from my invention.

40 45 50 55 60 65 66

The several bolts herein referred to and

which pass through the slot 2 of the standard 1, have a squared portion which fits between the walls of said slot, as clearly indicated in Figs. 3 and 6; such construction holding the bolts against turning when they are moved relatively to the slot 2, and while the thumb nuts are tightened to hold the connected parts to the standard.

When of wood, I preferably provide the block 7 with a metal reinforcing plate 7^a, clearly shown in Fig. 2, and in the sectional view, Fig. 6. If desired, the blocks 20 and 20^a may be reinforced in any suitable manner to prevent splitting and, as may be readily understood, any of the parts of my improved easel may be made of metal without departing from my invention.

I claim:

1. In an easel, the combination of a slotted standard, legs pivotally connected to the lower end of said standard and adapted to lie in parallel relation to said standard when folded, braces having their lower ends pivotally connected to said legs, a block slidably mounted with respect to said standard and connected to the upper ends of said braces, means for holding said block to the standard in adjusted positions, a third leg hinged to the lower end of the standard and extending rearwardly thereof, braces connected to said third leg, and a block slidably mounted with respect to the standard to which the upper ends of said third leg braces are pivotally connected.

2. In an easel, the combination of a slotted standard, legs pivotally connected to the lower end of said standard and adapted to lie in parallel relation to said standard when folded, braces having their lower ends pivotally connected to said legs, a block slidably mounted with respect to said standard and connected to the upper ends of said braces; said braces lying between the legs and the standard when in the folded condition, means for holding said block to the standard in adjusted positions, a third leg hinged to the lower end of the standard to swing in a plane substantially at right angles to the plane of the first mentioned legs rearwardly of the standard, braces connected to said third leg, and a block slidably mounted with respect to the standard to which the upper ends of said third leg braces are hinged.

3. In an easel, the combination of a slotted standard, legs pivotally connected to the lower end of said standard and adapted to lie in parallel relation to said standard when folded, braces pivotally connected to said legs, a block slidably mounted with respect to said standard to which the other ends of said braces are connected, means for holding said block to the standard in adjusted positions, a third leg hinged to the lower end of the standard and adapted to swing in a plane substantially at right angles to the

plane of the first mentioned leg, and braces adjustably mounted with respect to the standard pivotally connected to said third leg.

4. In an easel, the combination of a standard slotted throughout its length, a series of legs pivotally connected to the lower end of said standard and foldable in parallel relation thereto, adjustable connections between said legs and the standard movable in the slotted portion of the latter, a stretcher shelf or support carried by said standard, and an adjustable retaining member carried at the upper end of the slotted standard and movable in the slot of the same for engagement with objects mounted on said stretcher shelf.

5. In an easel, the combination of a slotted standard, a series of legs pivotally connected to the lower end of the same and foldable in parallel relation to said standard, adjustable connections between said legs and the standard; the latter being slotted to permit adjustment of said connections, bolts between said standard and said connections, and thumb nuts therefor retaining said connections in position.

6. In an easel, the combination of a slotted standard, a series of legs pivotally connected to the lower end of the same and foldable in parallel relation to said standard, adjustable connections between said legs and the standard; the latter being slotted to permit adjustment of said connections, bolts having squared portions disposed in the slot of said standard and holding said connections thereto, and thumb nuts therefor retaining said connections in position.

7. In a structure such as set forth in claim 1, a retaining rod carried by the upper end of the standard, an adjustable block to which said retaining rod is connected, and retaining means carried by said adjustable block for holding said retaining rod in adjusted positions.

8. In a structure such as set forth in claim 1, a palette support carried by the slotted standard comprising a cross-bar and folding arms pivotally connected thereto, and clamping means movably supported in the slotted portion of the standard for adjustably holding said palette support with respect to the standard.

9. In a structure such as set forth in claim 1, a retaining rod carried by the upper end of the standard, a vertically adjustable block to which said retaining rod is connected, eyebolt retaining members carried by said adjustable block for holding said retaining rod in adjusted positions; the latter being grooved to permit angular disposal of said retaining rod.

10. In a structure such as set forth in claim 1, a stretcher support or shelf for a picture or similar article adjustable with respect to the lower part of the standard, and a retaining rod for the upper edge of said picture ad-

justably supported by the upper end of said standard.

11. In a structure such as set forth in claim 1, a stretcher support or shelf for a picture or similar article adjustable with respect to the lower part of the standard, an adjustable retaining rod for the upper edge of said picture, and a movable block adjustably supported by the upper end of said standard for carrying said adjustable retaining rod.

In witness whereof I have signed this specification.

GEORGE W. CAHALL.
